Primary Examiner — L. A. Grabenstetter*Assistant Examiner* — Bethany Louise Mallino(74) *Attorney, Agent, or Firm* — Hawaii Patent Services; Nathaniel K. Fedde; Kenton N. Fedde(57) **CLAIM**

The ornamental design for a plant stand, as shown and described.

DESCRIPTION

FIG. 1 is a front, right, top perspective view of a plant stand, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view of the enlarged scale thereof.

The dashed broken lines in the figures are for the purposes of illustrating portions of the plant stand and form no part of the claimed design.

1 Claim, 8 Drawing Sheets(56)
